UNITED STATES PATENT OFFICE

POWELL EVANS AND MALCOLM P. STONEY, OF PHILADELPHIA, PENNSYLVANIA

DESIGN FOR A FIRE-EXTINGUISHER UNIT

Application filed July 9, 1930. Serial No. 36,305. Term of patent 14 years.

To all whom it may concern:

Be it known that we, POWELL EVANS and MALCOLM P. STONEY, citizens of the United States, residing in Philadelphia, Pennsylvania, have invented a new, original, and ornamental Design for Fire-Extinguisher Units, of which the following is a specification, reference being had to the accompanying drawing, forming a part hereof.

Fig. 1 is a front elevation of a fire extinguisher unit showing our new design;
Fig. 2 is a side elevation thereof; and
Fig. 3 is a bottom plan view thereof.

We claim:

The ornamental design for a fire extinguisher unit substantially as shown.

POWELL EVANS.
MALCOLM P. STONEY.
